SLIDE FASTENER

Gideon Sundback, Meadville, Pa., assignor to
Hookless Fastener Company, Meadville, Pa., a
corporation of Pennsylvania

Application October 26, 1929, Serial No. 402,729

5 Claims. (Cl. 24—205)

My invention relates to separable fasteners, particularly of the slide fastener type.

Slide operated separable fasteners have now come into general use in all kinds of clothing, luggage, receptacles and other articles. Such a fastener comprises a pair of stringers each having a series of closely spaced interlocking fastener elements attached along the beaded edge of a stringer tape by means of integral clamping jaws 10 engaging such beaded edge.

Various methods of building up this beaded edge have been devised, the most satisfactory of which heretofore, has been to sew a separate cord on each side of, and along one edge of a flat woven or braided fabric. This is the method described in my Patent No. 1,243,458, dated October 16, 1917.

Fastener stringers having beaded edges built up by attaching separate cords on opposite sides of the edges of tapes have proven much more satisfactory than stringers having a single enlarged cord, woven or braided in the edge of the tape. The stringer having two or more cords is superior to the single corded edge construction for the reason that, in the latter, the clamping jaws of the interlocking elements cut into the threads surrounding the cord at the rear side of the beaded edge thus decreasing the strength of the tape. It will be understood that in the single corded edge construction the weft threads of the tape pass around the cord and thus when the threads around the cord are broken the fabric is materially weakened. A further reason that the plural edge construction is superior is that it provides more abrupt shoulders for cooperation with the clamping jaws of the interlocking elements and thus permits a more positive connection.

My present invention contemplates a fastener construction having most or all of the advantages of the double corded edge construction disclosed in my patent mentioned above. At the same time, the sewing operation with its accompanying increase in cost of manufacture is wholly eliminated.

In one of its broadest aspects, my invention consists of a flexible strip with a separate member disposed along one edge and fastener elements clamped over the edge of said strip and member.

The general object of my invention is therefore to provide an improved fastener construction.

Another object is to provide a fastener of the type having a series of interlocking elements

along one edge with an improved beaded edge for holding the fastener elements.

Still another object is to provide an improved fastener stringer having a plurality of cords along one edge for engagement with the clamping jaws 60 of fastener elements, such cords being held in position only by said fastener elements.

Other objects and advantages of my invention will be apparent from the foregoing general statement and the following description of some 65 specific embodiments.

In the accompanying drawing I have shown for purposes of illustration one preferred embodiment and several modifications thereof which my invention may assume in practice. 70

In this drawing,

Fig. 1 illustrates one type of slide fastener with which my invention may be incorporated;

Fig. 2 is a transverse section through one of the stringers before attachment of the fastener 75 elements;

Fig. 3 is a similar transverse section after attachment of the fastener elements;

Fig. 4 is a transverse section similar to Fig. 3 showing a modified form of the invention; 80

Fig. 5 is a similar view showing another modification;

Fig. 6 is a transverse view through a stringer before attachment of the fastener elements showing still another modification; and 85

Fig. 7 is a section view showing a fourth modification.

Referring to the drawing, the complete fastener illustrated in Fig. 1 includes two mating stringers, each having a flexible strip 11 preferably of woven or braided tape and a series of fastener elements 12 attached along one of the longitudinal edges of the tape. A slider 13 is moved along the series of fastener elements to engage and disengage them in a manner well known in 95 the art. The fastener elements and slider herein shown are of the same general type as those disclosed in my former Patent No. 1,219,881.

As best illustrated in Fig. 2 the woven flexible strip 11 of each stringer has preferably an enlarged warp or cord 14 woven into the strip along one edge. A pair of twisted or braided cords 15 or 16, preferably twisted in opposite directions, are arranged on opposite sides of the tape 11 immediately behind the beaded edge of the tape 100 formed by the enlarged warp 14. In Fig. 3 one of the fastener elements 12 is shown on enlarged scale after attachment to the other part of the stringer. The fastener elements are held on by a pair of clamping jaws 17 and 18 which are 105 110

compressed upon the loose cords 15 and 16, the latter assuming a somewhat flattened form as clearly shown in Fig. 3. This provides a construction wherein the adjacent ends 19 and 20 of each of the fastener elements may interlock behind the cords 15 and 16 without interfering with the threads which make up the tape 11. After the clamping jaws 17 and 18 of the fastener elements are forced together to clamp the element on the tape, the cords 15 and 16 are securely held in position and effectively prevent relative movement or twisting of the fastener element. The beaded edge of the tape formed by the enlarged warp 14 serves to prevent movement 15 of the cords 15 and 16 from the edge of the tape.

In the modified construction shown in Fig. 4 a strip of flexible material 29 which may be of any desired fabric construction, leather or other suitable material, is folded over along the longitudinal edge as indicated at 30. On the side opposite the folded over portion is arranged a separate strip of material 31 to balance the portion 30. If desired, suitable guides may be provided for folding over the edge of the material 28 as it is fed into the machine and simultaneously the separate strip or cord 31 may be guided into the proper position. This construction provides a built up beaded edge for receiving the clamping jaws 17 and 18 of the fastener elements.

In Fig. 5 there is illustrated a modification particularly adapted for the attachment of fastener elements directly to leather or other similar material. A strip of leather 32, which may, in some instances, constitute an integral part of the article to which it is desired to attach the fastener, has its longitudinal edge skived or rolled to provide grooves 33 and 34 on opposite sides of the piece of material and spaced from the edge so as to leave a beaded edge portion 35. A pair of cords 36 and 37 are disposed on opposite sides and along the edge of the piece of material 32 and fit into the grooves 33 and 34 respectively, so that when the clamping jaws 17 and 18 of the fastener elements are clamped together, the cords or strips of material interlock in the grooves to hold them in position. The cords 36 and 37 may be secured to the leather before attachment of the fastener elements, or may be assembled therewith at the same time.

In Fig. 6, I have illustrated still another modification wherein a beaded edge tape construction similar to one of the types formerly used in fasteners is employed. This construction comprises a web portion 38 which may be braided or woven, and a tubular woven or braided portion 39 preferably integral with the web portion, the tubular portion enclosing a hard twisted cord 40. This is the construction referred to above, wherein in the weft threads at about the points indicated at 41 and 42 are frequently cut by the clamping jaws of the fastener elements. By the use of my invention a pair of separate protecting strips 43 and 44 may be disposed in contact with the surface of the corded edge portion adjacent the web portion so as to cover the points 41 and 42. These strips may be of fabric or any other suitable material.

The form illustrated in Fig. 7 is similar to that

shown in Fig. 4 except that the longitudinal edge of the material is given two folds as indicated at 45 and 46 so as to build up a larger beaded edge. A cord or a separate strip of material, 48 is arranged on the opposite side so as to balance the larger folded portion. This construction may prove to be more desirable when relatively thin fabrics are used.

As a result of my invention it will be noted that a novel fastener construction has been devised wherein most if not all of the advantages of the double corded edge stringer construction are secured, and at the same time the expense incurred in sewing on the cords or attaching same in any suitable manner is wholly eliminated.

While I have in this application shown and described specifically some forms which may be assumed by my invention in practice, it will be understood that these forms are merely for the purposes of illustration, and that various changes may be made and other forms produced without departing from the spirit of my invention the scope of which is defined in the following claims.

What I claim as my invention is:

1. In a slide fastener, a fastener stringer comprising a strip of fabric having a beaded edge formed integral therewith, a separate cord running along the longitudinal edge of said fabric strip but not attached directly thereto, said cord being disposed in contact with said beaded edge, and fastener elements having portions embracing said cord and beaded edge.

2. In a slide fastener, a fastener stringer comprising a fabric strip having a beaded edge, a separate flexible member disposed in contact with said beaded edge but not attached directly to said fabric strip, and a series of fastener elements having clamping portions engaging said beaded edge and flexible member.

3. In a slide fastener, a fastener stringer comprising a woven tape having an integral corded edge, a separate cord disposed on each side of said tape, said cord being disposed in contact with said corded edge and a series of interlocking elements having clamping jaws embracing said cords and corded edge and forming the sole means for attaching said cords to said tape.

4. In a slide fastener, a fastener stringer comprising a piece of flexible material, a cord disposed on each side of an edge of said piece of material, said material having means woven integrally therewith adapted to engage said cords tending to prevent movement of the cords from the edge of said material, and a series of fastener elements clamped around said cords and edge of material to hold said cords in place the clamping portions of the fastener elements being the sole means for holding the cords in position on the stringer.

5. In a fastener, a fastener stringer comprising a strip of fabric material, said strip having a beaded edge woven integrally therewith, a pair of flexible members disposed loosely on opposite sides of said strip in contact with said beaded edge, and fastener elements engaged around said flexible members and beaded edge.

GIDEON SUNDBACK.
